UNITED STATES PATENT OFFICE

2,475,383

QUICK DETACHABLE TELESCOPE SIGHT
MOUNT

Ralph R. Foster, Livingston, Mont., assignor of
one-half, by mesne assignments, to E. T. Lake,
Livingston, Mont.

Application March 28, 1947, Serial No. 737,782

5 Claims. (Cl. 42—50)

1

This invention relates to an improved mount adapted to be applied to and carried by a telescope sight for detachably mounting the sight on the receiver of a firearm, such as a rifle.

A particular object of the present invention is to provide a telescope sight mount by means of which the telescope sight can be mounted on a firearm receiver quickly and easily, without the use of tools and which will retain the telescope in a predetermined position relatively to the barrel of the firearm.

Still a further object of the invention is to provide a telescope sight mount which will eliminate the securing to the firearm of any apparatus for holding the telescope, thereby leaving nothing to interfere with the use of the regular sight of the weapon when the telescope is not applied thereto.

Still a further object of the invention is to provide a mounting which will detachably support a telescope on the receiver of a weapon without interference with the normal sights of the weapon and without the necessity of removing the sights therefrom.

Another object of the invention is to provide a mount adapted to be applied to the ejector opening of the receiver and which can be adapted to ejector openings of various weapons with only slight alterations of said openings and which will not interfere with the normal operation of the weapon, either with the telescope and mount applied thereto or removed therefrom.

Various other objects and advantages of the invention will hereinafter become more fully apparent from the following description of the drawings, illustrating a preferred embodiment thereof, and wherein:

Figure 1 is a side elevational view showing the mounting attached to a conventional telescope sight and in applied position on the receiver of a rifle;

Figure 2 is a top plan view thereof;

Figure 3 is an enlarged longitudinal sectional view taken substantially along a plane as indicated by the line 3—3 of Figure 2 and illustrating a portion of the receiver of the weapon in section;

Figure 4 is a fragmentary bottom plan view of the mount;

Figure 5 is a cross sectional view thereof taken substantially along a plane as indicated by the line 5—5 of Figure 1, and

Figure 6 is a similar view taken substantially along a plane as indicated by the line 6—6 of Figure 3.

Referring more specifically to the drawings, for the purpose of illustrating the application and use

2

of the invention, hereinafter to be described, 8 designates generally the receiver portion of a firearm such as a rifle of a conventional type and which is provided with an ejector opening 9 in the top thereof. The numeral 10 designates generally a conventional telescope sight to the barrel of which the telescope sight mount, designated generally 11 and comprising the invention, is shown applied.

10 The telescope mount 11 includes a pair of foot or base members, each designated generally 12 and each of which includes a base portion 13 having a split collar or sleeve 14 forming an integral upper extension thereof. The collar or sleeve 14 is provided with a lip 15 which projects from one side of the split portion thereof and which is apertured as seen at 16 to receive screw fastenings 17 which extend therethrough and into threaded recesses 18 of the base portion 13, all as best illustrated in Figure 5. The sleeve portion 14 of each foot or base member 12 is adapted to engage around a portion of the barrel of the telescope 10 and by tightening the fastenings 17 the sleeve or collar portions 14 are clamped to the telescope barrel for securing the members 12 thereto. The base portions 13 of the two members 12 are disposed in alignment and, as illustrated in Figure 5, each of said portions is provided with a concave under side 19 adapted to fit flush against a portion of the upper side of the receiver 8. Obviously, the shape of the under surfaces 19 could vary to conform to the shape of the upper portion of the receiver of any particular firearm on which the mounting 11 is adapted to be applied.

25 As clearly illustrated, the two foot members 12 are secured to the barrel of the telescope 10 in spaced relationship to one another and a pair of collar members, designated generally 20 and 21 are mounted on the telescope barrel between said foot members 12. As best seen in Figure 6, the collar member 20 includes a collar or sleeve portion which is split similar to the portion 14 and which has a lip 22 which is apertured to receive screw fastenings 23 which extend therethrough into threaded recesses 24 of an enlarged base portion 25 of said collar 20. It will be readily apparent that by tightening the fastenings 23 the collar 20 can be tightened into clamping engagement with the barrel of the telescope 10 for frictionally securing it thereto adjacent the foot member 12, located nearest the rear end of the telescope 10 and with the base portion 25 thereof in alignment with the base portions 13 of said members 12. As seen in Figure 6, the base portion 25 is provided with a restricted stem which projects substan-

tially radially from said collar 20 and which is designated 26. The stem 26 is provided at its free end and on the outer side thereof with a laterally projecting lug or extension 27 having an outwardly and downwardly inclined upper surface 28, for a purpose which will hereinafter become apparent.

A sleeve 29 is slidably disposed on the barrel of the telescope 10, between the collar 20 and the forwardmost foot member 12 and constitutes the body portion of the collar 21 which is slidably disposed with respect to the telescope. The sleeve 29 is provided with an integral depending stem 30, which projects radially therefrom and which forms a part of said collar 21. The stem 30 at its lower or outer end is provided with an extension 31 which projects downwardly and forwardly therefrom and away from the stem 26 and which is likewise provided with an outwardly and downwardly inclined upper edge 32.

An elongated sleeve 33 is loosely disposed around the barrel of the telescope 10 and has one end thereof engaging over the upper portion of the collar 20 and which end is provided with a notch 34 in the underside thereof to accommodate the base portion 25 of the collar 20. The opposite end of the sleeve 33 engages over the sleeve 29 of the collar 21 and is provided with a longitudinal notch 35 for accommodating the stem 30 of said collar 21.

An expansion coiled spring 36 is disposed around the telescope barrel and within the sleeve 33, between the collar units 20 and 21 for urging said collar unit 21 outwardly or forwardly with respect to the collar unit 20 and against the forwardmost foot member 12, as illustrated in Figure 4. The sleeve 33 normally moves with the collar unit 21 and may be pressed to fit upon its sleeve 29, if desired.

As best seen in Figure 3, the rear end of the ejector opening 9 of the receiver 8 is provided with a notch 37 and said receiver is provided with an inclined under surface 38 extending toward the inner end of said notch 37. The opposite, forward end of the ejector opening 9 has a recess 39 formed therein and which is shaped to receive the tapered forward end of the extension or lug 31.

To apply the telescope mount 11 to the receiver 8, the stem 26 is engaged in the notch 37 and the sleeve 33 is then manually engaged and moved rearwardly of the telescope 10 for retracting the collar unit 21 away from the forward foot member 12 so that the lug 31 thereof can be positioned in the forward end of the ejector opening 9. The sleeve 33 is then permitted to move forward for engaging the tapered forward end of the lug 31 in the recess 39 and by engagement of which the upper surface 32 thereof through cam action with the upper surface of the notch or recess 39, will cause the mount 11 to be drawn downwardly until the base portions 19 rest flush on the top of the receiver 8. At the same time, the lug or extension 27 of the fixed collar unit 20 will be seated in its position of Figure 3 and with its upper surface 28 in substantially flush engagement with the surface 38 of the receiver to provide a camming action for the rear portion of the mounting unit 11, so that the telescope mounting 11 is cammed downwardly near each end thereof to insure proper seating of the surfaces 19 with the upper side of the receiver 8 and so that the longitudinal axis of the telescope 10 will be correctly disposed with respect to the axis of the bore of the firearm, of which the receiver 8 forms a part. By

manually retracting the sleeve 33, with the collar unit 21 which is secured thereto, against the action of the spring 36 in a direction from left to right of Figures 1 to 3, the lug or extension 31 will be disengaged from the notch 39 so that the telescope mount 11 may be rocked upwardly at its forward end and disengaged from the receiver 8, thus enabling the mount to be applied to or removed from said receiver 8 without the use of any tools. Further, the telescope 10 when supported by the mount 11 will not interfere with the normal sight of the weapon or with the normal operation thereof, including ejection of the cartridge cases through the opening 9. When the sight and mount are removed, the weapon of which the receiver forms a part may be utilized in a conventional manner and with a conventional sight and there will be no projections or protruding elements thereon as is conventionally required in affording a means for mounting a telescope sight.

It will also be readily apparent that the mount 11 can be adapted to ejector openings of receivers of various rifles and other firearms by providing notches or recesses in the ends thereof for reception of the lugs 27 and 31 and that the distance between said lugs, when in an applied position on a receiver, may obviously be varied by the adjustability afforded by the spring 36 and springs of different lengths may be employed if required.

Various other modifications and changes are likewise contemplated and may obviously be resorted to, without departing from the spirit or scope of the invention as hereinafter defined by the appended claims.

I claim as my invention:

1. In a mount for telescope sights for firearms, a lug fixedly secured to the barrel of a telescope sight and projecting substantially radially therefrom, a second lug slidably disposed on said sight barrel and projecting substantially radially therefrom, said lugs having substantially laterally extending projections at their outer ends and projecting therefrom in directions away from one another and adapted for detachably engaging in the ends of the ejector opening of a firearm receiver, spring means interposed between said lugs for urging the slidably mounted lug away from the fixed lug for yieldably and detachably retaining said lug extensions in engagement with the ends of the ejector opening for mounting the telescope on the receiver, and a sleeve slidably disposed on the sight barrel and substantially enclosing said spring means, said sleeve being connected to and movable with said slidably mounted lug and being movable relatively to the fixed lug.

2. In a mount for telescope sights for firearms, a lug fixedly secured to the barrel of a telescope sight and projecting substantially radially therefrom, a second lug slidably disposed on said sight barrel and projecting substantially radially therefrom, said lugs having substantially laterally extending projections at their outer ends and projecting therefrom in directions away from one another and adapted for detachably engaging in the ends of the ejector opening of a firearm receiver, spring means interposed between said lugs for urging the slidably mounted lug away from the fixed lug for yieldably and detachably retaining said lug extensions in engagement with the ends of the ejector opening for mounting the telescope on the receiver, and foot members fixedly secured to the sight barrel, said foot members having base portions constructed and arranged to

fit flush against portions of the receiver when the lugs are in engagement with the ends of the ejector opening for combining with said lugs to detachably maintain the telescope sight in a predetermined position relatively to the receiver.

3. In a mount for telescope sights for firearms, a lug fixedly secured to the barrel of a telescope sight and projecting substantially radially therefrom, a second lug slidably disposed on said sight barrel and projecting substantially radially therefrom, said lugs having substantially laterally extending projections at their outer ends and projecting therefrom in directions away from one another and adapted for detachably engaging in the ends of the ejector opening of a firearm receiver, spring means interposed between said lugs for urging the slidably mounted lug away from the fixed lug for yieldably and detachably retaining said lug extensions in engagement with the ends of the ejector opening for mounting the telescope on the receiver, a split collar forming an integral part of said fixed lug and having means for detachably clamping the collar to the sight barrel, and a sleeve forming a part of said slidably mounted lug and slidably disposed on said barrel.

4. In combination with an ejector opening of a firearm receiver, said receiver being provided with recesses opening into the ends of the ejector opening, a telescope mount comprising a lug fixedly secured to the barrel of a telescope sight for engagement with one of said recesses, a second lug slidably disposed on the sight barrel, spring means interposed between said lugs for urging the slidable lug in a direction away from the fixed lug and into engagement with the other of said recesses for detachably mounting the telescope sight on the receiver, foot members fixed to the sight barrel and having base portions constructed and arranged to engage flush against external por-

tions of the receiver when said lugs are in engagement with the recesses.

5. In combination with an ejector opening of a firearm receiver, said receiver being provided with recesses opening into the ends of the ejector opening, a telescope mount comprising a lug fixedly secured to the barrel of a telescope sight for engagement with one of said recesses, a second lug slidably disposed on the sight barrel, spring means interposed between said lugs for urging the slidable lug in a direction away from the fixed lug and into engagement with the other of said recesses for detachably mounting the telescope sight on the receiver, foot members fixed to the sight barrel and having base portions constructed and arranged to engage flush against external portions of the receiver when said lugs are in engagement with the recesses, and said lugs and the recesses engaged thereby having coating cam surfaces for urging the telescope mount inwardly of the receiver for cooperation with said foot members for yieldably retaining the telescope sight in a predetermined position relatively to said receiver.

RALPH R. FOSTER

It is hereby certified that errors appear in the above numbered patent requiring correction as follows:

In the grant, lines 1 to 3, for "assignor of one-half, by mesne assignments, to E. T. Lake, of Livingston, Montana," read *assignor, by direct and mesne assignments, of one-half to Robert R. Hardgrove and one-half to E. T. Lake, both of Livingston, Montana,;* line 13, for "Ralph R. Foster and E. T. Lake, their heirs" read *Robert R. Hardgrove and E. T. Lake, their heirs;* in the heading to the printed specification, lines 4 to 6 inclusive, for "assignor of one-half by mesne assignments, to E. T. Lake, Livingston, Mont." read *assignor, by direct and mesne assignments, of one-half to Robert R. Hardgrove and one-half to E. T. Lake, both of Livingston, Mont.* as shown by the record of assignments in this Office;

and that the said Letters Patent should be read with these corrections therein that the same may conform to the record of the case in the Patent Office.

Signed and sealed this 13th day of December, A. D. 1949.
